UNITED STATES PATENT OFFICE.

CLAES W. BOMAN, OF NEW YORK, N. Y., ASSIGNOR TO THE EAGLE PENCIL COMPANY, OF NEW YORK.

DESIGN FOR A PEN-CASE.

SPECIFICATION forming part of Design No. 20,158, dated September 23, 1890.

Application filed August 28, 1890. Serial No. 363,356. Term of patent 7 years.

To all whom it may concern:

Be it known that I, CLAES W. BOMAN, of the city, county, and State of New York, have invented a new and original Design for

- 5 Pen-Cases, of which the following is a specification, reference being had to the accompanying drawing, which represents a pen-case of my design, consisting of a pen-handle A and a pen tip or holder B.
- 10 The handle has a body *a* of cylindrical contour, with a rounded rear end and an annular head or projection *b* near its front end. The portion *c* of the tip which adjoins the handle

is cylindrical in contour, and thence it extends by a bevel *d* to the portion *e* of smaller cylindrical contour, which portion terminates in a somewhat abrupt annular flare *f*.

What I claim, and desire to secure by Letters Patent, is—

The design for pen-cases, as shown.

In testimony whereof I have hereunto set my hand this 27th day of August, A. D. 1888.

CLAES W. BOMAN.
